INVENTOR

James Hogg

United States Patent Office.

JAMES HOGG, OF PHILADELPHIA, PENNSYLVANIA, ASSIGNOR TO FLEMING BROTHERS, OF SAME PLACE.

Design No. 4,704, dated March 14, 1871.

DESIGN FOR A STOCKING.

The Schedule referred to in these Letters Patent and making part of the same.

I, JAMES HOGG, of the city of Philadelphia and State of Pennsylvania, have invented and produced a new and original Design for Stocking, of which the following is a specification.

The nature of my design is fully represented in the accompanying photographic illustrations and diagrams 1 2.

The diagram 1 represents a single figure, *b*, and the diagram 2 a succession of several figures, arranged as shown in the photographic illustrations, to which reference is made.

The design consists of vertical lines, *A*, of woven figures, *b*, of rhomboidal form, each alternate one pro-

jecting at one end beyond the ones contiguous thereto, as shown.

The long sides of the figures *b* are brought together. Each alternate figure *b* is reversed from the preceding one, or, as it were, turned over, so as to bring the acute angles and the oblique angles together at each side of the vertical lines of the figures, as represented.

I claim as my invention—

The design for stocking, as shown in the accompanying photographic illustrations and diagrams 1 2.
